His Attorney

UNITED STATES PATENT OFFICE.

ALBERT H. SIMMONS, OF OAK PARK, ILLINOIS, ASSIGNOR TO EDISON ELECTRIC APPLIANCE COMPANY, INCORPORATED, OF CHICAGO, ILLINOIS, A CORPORATION OF NEW YORK.

ELECTRIC CONNECTER.

Application filed March 25, 1924. Serial No. 701,850.

My invention relates to electric connectors, and has for its object the provision of a simple and reliable connector which may be manufactured and assembled at relatively low cost.

More specifically, my invention relates to detachable plug connectors such as are used on electric appliances, although my invention may also be used in connectors providing a more or less permanent connection. In carrying out my invention, I provide an improved arrangement of the various parts such that the metallic parts can be easily and quickly made by stamping them from sheet metal, and the various parts quickly assembled.

For a more complete understanding of my invention, reference should be had to the accompanying drawing, in which Fig. 1 is a perspective view of an electrical connector embodying my invention, Fig. 2 is a fragmentary view, while Fig. 3 is an exploded view illustrating various parts and the method of assembling.

Referring to the drawing, I have shown my invention in one form as applied to electric connectors of the quickly detachable type such as used on electric toasters, flat irons and other electric appliances. My invention is not limited, however, to this type of connector. The connector comprises two cooperating insulating members 10 and 11 which are similar in construction and are provided with recesses for securing contact members 12 and 13. These insulating members may be molded or otherwise formed of a suitable insulating material. As shown, the member 10 is provided with a recess 14 which cooperates with a recess 15 in the member 11 when the two are placed together, so as to form a space in which the contact member 13 is held. In a similar manner, contact member 12 is secured in a space formed by a recess 16 in member 10 and a recess 17 in member 11. It will be understood that the contact members 12 and 13 are secured in their respective spaces by the securing of the members 10 and 11 together. Leading from the recesses 14 and 15, respectively, are grooves 18 and 19, which cooperate to form an aperture for an electrical conductor 20 which is electrically connected to contact member 13, while leading from recesses 16 and 17 are similar

grooves 21 and 22 which cooperate to form an aperture for an electrical conductor 23 which is electrically connected to contact member 12. The contact members may be of any suitable form adapted to form an electrical connection with contact pins or studs on the appliance or device with which an electrical connection is to be made. The conductors 20 and 23 may be secured to the contact members by means of screws 24 or other means for forming a suitable contact.

The conductors 20 and 23 are wrapped one or more turns around a cross-bar 25 made of suitable insulating material, such as hard wood, bakelite or other composition. This cross-bar extends transversely of the members 10 and 11 and is secured adjacent to the ends of the members by means of two oppositely disposed metallic clamping plates 26 and 27 which fit in slight recesses 26^a and 27^b on the outer sides of the insulating members 10 and 11, the recesses being of such depth that the plates are flush with the members. Preferably, the ends of the members 10 and 11, with which the cross-bar 25 is in engagement, are grooved, as shown in the drawing, so as to form an approximately half round groove in which the cross-bar is seated. Central slots or notches 28 and 29 are formed in the ends of the members 10 and 11 adjacent the cross-bar, to provide space for the turns of the conductors 20 and 23, which are wrapped around the cross-bar. As shown, the cross-bar may be and is shown as provided with a slightly enlarged central portion 30, which fits in the space formed by slots 28 and 29, thereby tending to secure the cross-bar against movement in an endwise direction. This enlarged portion is not indispensable, however, since plates 26 and 27 perform the same function.

The conductors 20 and 23 lead out through a helically coiled spring support 31, which serves to relieve the conductors of bending strains at the point of entrance to a supporting member 32 for the spring. This member 32 is approximately semi-spherical in shape and fits over the turns of the conductors 20 and 23 wrapped around the cross bar. It is provided with a centrally located tubular neck 33, in which the spring 31 is inserted for a short distance and secured by expanding one or more of the end turns 34. The

member 32 is also provided with laterally extending, oppositely disposed, semi-cylindrical bearing projections 35 and 36 which fit on and rotatably engage with the cross-bar 25.

The two clamping plates 26 and 27 are similar in construction and are each provided with a portion 37 which is struck outward in the form of a segment of a sphere. These spherical portions 37 engage on opposite sides with the spherical portion of the member 32, the two plates 26 and 27 being also shaped to provide an enlarged aperture 38 for the neck 33 of member 32, whereby the member 32 is free to move on its bearings 35 and 36 through a small angle. Oppositely disposed cylindrical clamping portions 39 and 40 are provided on each side of the plates 26 and 27. These portions 39 and 40 fit over the bearing projections 35 and 36 of member 32. A substantially ball and socket joint is thus formed between member 32 and the insulating members 10 and 11, although angular movement is limited to one axis only, that is, the axis of cross-bar 25. The two clamping plates 26 and 27 are in abutting relation at each side of member 32, so as to form substantial joints 41 and 42. As shown, the various parts of the connector are held together by means of two bolts 43 and 44. The bolt 43 passes through the insulating members 10 and 11 and also through the plates 26 and 27, while the bolt 44 passes through the members 10 and 11 only. Preferably the cross-bar 25 is provided at its ends with knobs 45 and 46 which may be grasped to facilitate the application and removal of the connector.

It will thus be observed that the plug is constructed of parts which are very simple and economical to manufacture. The metallic parts are simple stampings. Also, the assembly of the connector is greatly simplified by the construction of the parts. The parts may be assembled on a suitable support and then secured together by driving in the bolts 43 and 44 with an automatic screw driver. In accordance with this method, the nuts 47 and 48 (Fig. 3) for the bolts 43 and 44 are placed on a suitable support in the proper spaced relation. The nut 47 is preferably provided with a cylindrical extension 49 which projects through the aperture in the plate 27 which is next placed over the nut 47. An insulating member 11 is then placed on the plate member, the insulating member having the outer portions of the apertures 50 and 51 for the clamping bolts enlarged to receive the extension of nut 47 and nut 48. The next step is to place the spring guard 31, supporting member 32, cross-bar 25, the conductors 20 and 23 and the contacts 12 and 13, properly assembled together, in the correct positions with relation to the insulating member 11. As thus

far assembled, the connector is shown in Fig. 2. To complete the assembly the remaining insulating member 10 and plate 26 are laid in place, and the bolts 43 and 44 inserted in the holes provided for them and driven into the nuts 47 and 48 to clamp the parts tightly together.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

1. An electric connector comprising co-operating insulating members, contacts secured between said insulating members, a cylindrical cross bar, conductors connected to said contacts and wrapped around said cross bar, flexible supporting means for said conductors pivotally engaging said cross bar, and plates securing said cross bar and supporting means to said insulating members while providing for rocking movement of said supporting means on said bar. 95

2. An electric connector comprising a pair of cooperating insulating members provided with recesses, contacts secured in said recesses, a cylindrical cross bar having a projection at each end forming finger holds, conductors connected to said contacts and wrapped around said cross bar, a coiled spring support for said conductors, a supporting member for said spring seated on said cross bar so as to be pivoted thereon, and plates securing said supporting member and said cross bar in a definite relation with said insulating member while providing for limited angular movement of said supporting member on said cross bar. 105 110

3. An electric connector comprising a pair of cooperating insulating members provided with recesses, contacts secured in said recess, a cylindrical cross bar made of insulating material, conductors connected to said contacts and wrapped around said cross bar, a coiled spring support for said conductors, a supporting member for said spring, projections on said supporting member fitting on said cross bar whereby said supporting member is pivoted on said cross bar, and plates securing said cross bar and supporting member in a predetermined relation with said insulating members. 115

4. An electric connector comprising a pair of insulating members provided with matched recesses, contacts secured in said recesses, a cylindrical cross bar, conductors connected to said contacts wrapped around said bar, supporting means for said conduct- 120 125 130

- tors pivotally bearing on said bar, said supporting means being provided with an enlarged portion fitting over the turns of said conductors wrapped around said bar, and means for securing said cross bar and said supporting means in a predetermined relation with said insulating members while permitting pivotal movement of said supporting means on said bar.
- 10 5. An electric connector comprising a pair of insulating members provided with matched recesses, contacts secured in said recesses, a cylindrical cross bar, insulated conductors connected to said contacts wrapped around said cross bar, supporting means for said conductors provided with a substantially semi-spherical portion fitting over the turns of said conductors wrapped around said bar, projections on said semi-spherical portion forming bearing surfaces fitting on said cross bar, and clamping plates for securing said supporting means and said cross bar in a predetermined relation with said insulating members while providing
- 15 20 25 for limited pivotal movement of said supporting means on said cross bar, said clamping plates being provided with portions fit-
- ting over said semi-spherical portions and said projections.
6. An electric connector comprising a pair 30 of insulating members provided with cooperating recesses, contacts secured in said recesses, a cylindrical cross bar provided with a knob at each end forming finger holds, insulated conductors connected to said contacts and wrapped around said cross bar, a coiled spring support for said conductors, a supporting member for said spring provided with a substantially semi-spherical portion, 35 projections on said supporting member rotatably cooperating with said cross bar, plates provided with substantially semi-spherical portions and projections cooperating respectively with the semi-spherical portion and projections of said supporting members 40 so as to secure said supporting member in a predetermined relation with said insulating members while providing for limited angular movement of said supporting member, and bolts securing said plates 45 and insulating members together.

In witness whereof, I have hereunto set my hand this 21st day of March, 1924.

ALBERT H. SIMMONS.
